FOREIGN PATENT DOCUMENTS

CA 800836 12/1968

Primary Examiner—Dominic Simone

(74) Attorney, Agent, or Firm—Calfee, Halter & Griswold, LLP

(57) **CLAIM**

The ornamental design for a paint container lid, as shown and described.

DESCRIPTION

FIG. 1 is a perspective view a first embodiment of a paint container lid embodying our design;

FIG. 2 is a side view of the paint container lid shown in FIG. 1 thereof;

FIG. 3 is a top plan view of the paint container lid shown in FIG. 1 thereof;

FIGS. 4 and 5 are perspective views of a second embodiment of a paint container lid embodying our design;

FIGS. 6 and 7 are side views of the paint container lid shown in FIGS. 4 and 5 thereof;

FIG. 8 is a top plan view of the paint container lid shown in FIGS. 4 and 5 thereof;

FIG. 9 is a perspective view of a third embodiment of a paint container lid embodying our design;

FIG. 10 is a side view of the paint container lid shown in FIG. 9 thereof; and,

FIG. 11 is a top plan view of the paint container lid shown in FIG. 9 thereof.
